UNITED STATES PATENT OFFICE.

NED G. FRANKLIN, OF INDEPENDENCE, MISSOURI, ASSIGNOR OF ONE-HALF TO I. A. SMITH, OF INDEPENDENCE, MISSOURI.

RAIL JOINT.

Application filed September 20, 1926. Serial No. 136,535.

My invention relates to rail joints and more particularly to a rail joint comprising a pair of rail engaging members and means for locking said rail engaging members in position on adjoining rail ends.

It is a purpose of my invention to provide a rail joint that is adapted to eliminate rattle when wheels pass over the joint and to also provide means for bracing or strengthening the joints between the adjoining rails.

It is a further purpose of my invention to provide a rail joint which will eliminate the battered ends of rails and prevent the breaking of the bolts for securing the rail ends to the plate members of the joint. The joint furthermore will not slip or creep when properly applied, and is very easy to apply and simple in construction.

More particularly my invention comprises a rail joint made up of a pair of plates engaging opposite sides of the rail ends and having portions extending under the base portions of the rails preferably in overlapping arrangement, one of said plates being provided with hook-like flanges that are adapted to be engaged by lock members having hook-like members engaging with said flanges and also having portions engaging around the base portion of the rail.

Other objects and advantages of the invention will appear as the description of the accompanying drawings proceeds. However, I desire to have it distinctly understood that I do not intend to limit myself to the exact details shown or described, but that I intend to include as part of my invention all such obvious changes and modifications of parts as would occur to a person skilled in this art and as would fall within the scope of the claims.

In the drawings:

Fig. 1 is a fragmentary perspective view of the adjoining ends of two rails, showing my improved joint applied thereto.

Fig. 2 is a similar view looking upwardly toward the under side of the rail.

Fig. 3 is a perspective view of the component parts of the rail joint separated, and

Fig. 4 is a transverse sectional view of the rail joint taken on line 4—4, Fig. 2.

Referring in detail to the drawings:

My improved joint is shown as being applied to the rail members 10 at adjoining ends thereof, the ends of the rails being cut so as to form a joint of the usual character

between the ends thereof. My improved rail joint comprises a pair of plate members 11 and 12 which have the ribbed web portions 13 and 14 engaging with the web portion 15 of the rails. Said plates are provided with openings 16 and 17 in the members 11 and 12 respectively, through which the bolts 18 which may be provided with nuts 19 and washers 20 for securing the plate members 11 and 12 together may be projected.

The plate member 11 is provided with an outwardly offset portion 21 terminating in an upwardly extending portion 22 which conforms substantially to the shape of the side portion of the heads 23 of the rails 10. Said member 11 is further provided with an outwardly inclined portion 24 extending from the lower web engaging rib portion 13 and engaging with the upper inclined face of the base portion 25 of the rails, and terminates in a flange portion 26 engaging under the base portions 25 of the rails and extending substantially entirely across said base portions.

The plate member 12 is provided with an upwardly directed rib portion 27 which engages on the under side of the head portions 23 of the rails but does not extend upwardly along the sides of the rails at the head portion thereof, the plate member 12 being placed on the inside sides of the rails and being made so as to end short of the side face of the head portion 23 on each of the rails so as not to interfere with the engagement of the wheels and flanges on the wheels with said rails. The plate member 12 is further provided with a rib 28 extending outwardly therefrom and with an outwardly inclined portion 29 lying along the upper faces of the base portions 25 of the rails and conforming thereto. The member 12 furthermore has a hook-line flange portion 30 extending around the edges of the rail members and overlapping the edge of the base portion 26 of the member 13. The plate 12 is cut away on opposite sides of the hook-like portion 30 as indicated at 31 in Fig. 4 and the hook-like portion 30 has a rib 32 engaging in a groove 33 in the member 11.

The flange portion 26 of the plate 11 is provided with a pair of arcuate hook-like locking flanges 34 and 35 which curve in opposite directions. Engaging with the arcuate hook flange 34 is the locking member 36

- which has a similar arcuate hook flange 37 which is adapted to interlock with the flange 34. The member 36 is rotated into position in the manner indicated by the arrow in Fig. 3, and is further provided with a hook-like flange 38 which engages around the base portion of the rail as shown in Fig. 1. The locking member 39 is similar to the locking member 36 and is provided with a hook flange 40 that interlocks with the flange 35 and is placed in position in a similar manner as is the member 35. Said locking member is further provided with a hook flange 41 engaging around the base of the rail.
- 15 An arcuate rib 42 is provided on the member 11 concentric with the hook flange 34 and a similar rib 43 is provided concentric with the flange 35. The members 36 and 39 are notched at 44 and the member 12 is notched at 45 to provide notches to accommodate the spikes 46. The member 11 is notched at 47 to accommodate the projecting portion 48 of the flange 38 and is also notched at 49 to accommodate the projecting portion 50 on the flange 41.

It will be seen that when the locking members are in position the members 11 and 12 will be firmly locked to the rail, and as the locking members also engage with the edges 30 of the member 12 at the cut out portions 31, all the parts will be held against relative movement by means of said locking members.

What I claim and desire to secure by Letters Patent is:—

35 1. In a rail joint, a pair of angle bars, each comprising a base flange and a locking member engaging the base flange of one of said angle bars, said locking member having interengaging, curved, hook-like 40 flanges thereon to interlock said member and said base flange.

2. In rail joint, a pair of angle bars, each comprising a base flange, and a pair of locking members engaging with one of said 45 flanges, said locking members having curved hook-like flanges thereon and said base flange having oppositely directed, curved hook-like flanges interlocking with the flanges on said locking members.

50 3. The combination with a pair of rails, of means for connecting said rails comprising a pair of angle bars, having base flanges extending around the bases of the rails and extending toward each other in engagement 55 with the under sides of said bases and locking members engaging one of said flanges, said locking members and said flange having interengaging means thereon to interlock said members with said flange and said 60 locking members each having a hook-like

flange engaging around the edge of the base portion of one of said rails.

4. The combination with a pair of rails, of means for connecting said rails comprising a pair of angle bars, having flanges extending around the bases of the rails and extending toward each other in interengagement with each other and locking members engaging one of said flanges, said locking members and said flange having interengaging hook-like flanges thereon to interlock said members with said flange and said locking members each having a hook-like flange engaging around the edge of the base portion of one of said rails.

5. The combination with a pair of rails, of means for connecting said rails comprising a pair of angle bars, having flanges extending around the bases of the rails and extending toward each other in interengagement with each other and locking members engaging one of said flanges, said locking members and said flange having interengaging, oppositely curved, hook-like flanges thereon to interlock said member with said flange and said locking members each having a hook-like flange engaging around the edge of the base portion of one of said rails.

6. The combination with a pair of rails, of means for connecting said rails comprising a pair of angle bars having flanges extending around the bases of the rails and extending towards each other in interengagement with each other and having flanged portions engaging the head portions of said rails, and locking members engaging one of said flanges, said locking members and said flange having interengaging means thereon to interlock said members with said flange and said locking members each having a hook-like flange engaging around the edge of the base portion of one of said rails.

7. The combination with a pair of rails, of means for connecting said rails comprising a pair of angle bars having flanges extending around the bases of the rails and extending in overlapping engagement with each other and having flanged portions engaging the head portions of said rails, one of said flanged portions being longer than the other thereof, and locking members engaging one of said flanges, said locking members and said flange having interengaging means thereon to interlock said members with said flange and said locking members each having a hook-like flange engaging around the edge of the base portion of one of said rails.

In testimony whereof I affix my signature.

NED G. FRANKLIN.
